Primary Examiner—Louis S. Zarfas*Assistant Examiner*—Eric Watterson*Attorney, Agent, or Firm*—Myron B. Kapustij; Leon E. Redman[57] **CLAIM**

The ornamental design for a shower escutcheon and handle, as shown and described.

DESCRIPTION

FIG. 1 is a front, left perspective view of a shower escutcheon and handle;

FIG. 2 is a front, right perspective view thereof;
FIG. 3 is a top plan view thereof;
FIG. 4 is a front elevational view thereof;
FIG. 5 is a left side elevational view thereof;
FIG. 6 is a right side elevational view thereof;
FIG. 7 is a bottom plan view thereof;
FIG. 8 is a cross-sectional view taken along line 8—8 in
FIG. 1; and,

FIG. 9 is a cross-sectional view taken along line 9—9 in
FIG. 2.

The broken line showing of the screws in FIGS. 1, 2 and 4
is for purposes of illustration only and forms no part of the
claimed design.
